United States Patent Office

Des. 205,166
Patented June 28, 1966

205,166

JUG

Warren L. Price, 1247 Clinton Place, Elizabeth, N.J.

Filed Sept. 2, 1964, Ser. No. 81,558

Term of patent 14 years

(Cl. D58—5)

FIG.1

The side opposite that seen in FIGURE 2 is a mirror image of the side shown and the rear is plain and unornamented.

I claim:

The ornamental design for a jug, substantially as shown and described.
